CLAIM

The ornamental design for a double-headed eyeshadow stick, as shown and described.

DESCRIPTION

FIG. 1 is a perspective view of a double-headed eyeshadow stick showing my new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof; and,

FIG. 8 is an exploded view thereof.

A bracket in FIG. 8 is employed to show the association of elements of the double-headed eyeshadow stick and forms no part of the claimed design.

The broken lines shown in the drawings are for the purpose of illustrating portions of the double-headed eyeshadow stick that form no part of the claimed design.
